UNITED STATES PATENT OFFICE

102,350

DESIGN FOR A TEACUP OR SIMILAR ARTICLE

Karl Bayreuther, Selb, Germany, assignor to The Rosenthal China Corporation, New York, N. Y., a corporation of New York

Application September 25, 1935, Serial No. 58,706

Term of patent 14 years

To all whom it may concern:

Be it known that I, Karl Bayreuther, a citizen of Germany, residing at Selb, Bavaria, Germany, have invented a new, original, and ornamental Design for a Tea Cup or Similar Article, of which the following is a specification, reference being had to the accompanying drawing, forming a part thereof.

Fig. 1 is a side elevational view of the tea cup or similar article showing my design; and

Fig. 2 is a sectional view thereof, taken along the line 2—2 of Fig. 1.

The body of the cup embodying my new design has a somewhat shallow or flat appearance with a pronounced base outline and with the contour of its peripheral top projecting outwardly with a distinct lip effect which merges into the

curvature of the side, and the handle is curved to harmonize with the side and rises upwardly beneath the aforesaid top lip which overhangs it, and said handle is curved outwardly and then around backwardly to the side of the cup meeting the same at an abrupt angle on the lower edge and a sharp curve on the adjoining edge, said handle having the appearance of a horizontally projecting curved member more or less flat or depressed in appearance so as to harmonize with the shallow or flat style of the complete cup design.

I claim:

The ornamental design for a tea cup or similar article as shown and described.

KARL BAYREUTHER.
